UNITED STATES PATENT OFFICE.

JOHN T. NEEDHAM, OF BAYONNE, NEW JERSEY.

CARRIER FOR PNEUMATIC-DESPATCH-TUBE APPARATUS.

1,176,918.

Specification of Letters Patent. Patented Mar. 28, 1916.

Application filed November 30, 1914. Serial No. 874,636.

To all whom it may concern:

Be it known that I, JOHN T. NEEDHAM, a subject of the King of Great Britain, a citizen of Canada, and resident of Bayonne, 5 county of Hudson, and State of New Jersey, have invented certain new and useful Improvements in Carriers for Pneumatic-Despatch-Tube Apparatus, of which the following is a specification.

10 One of the main objects of the invention is to provide a carrier of simple construction having means for holding the message slips in the carrier, said means being adapted to be turned to extend outwardly beyond the 15 end of the carrier, to thereby prevent the open carrier being placed in a transmission tube.

The invention is applicable to carriers having only one head, the other end of the 20 carrier being open to receive the message slips. It frequently happens that carriers of this kind are placed in the transmission tube with the slip holding means improperly adjusted. With my invention the slip holding 25 means is of such construction that if it is not in proper position for holding the message slips, the said holding means will serve as a guard to prevent the carrier being placed in a tube and will serve as a warning to the operator that the carrier is not 30 in proper condition to be transmitted.

A further object of the invention is to provide a message holding clip which will fit entirely within the carrier so that it will 35 not be in danger of damage from other carriers which contact with it either in the tube or in the basket which receives the carriers from the transmission tube.

Another object of the invention is to provide a peculiar form of holding clip which will effectually seal the message slips in the 40 carrier during the travel of the carrier.

There are other important objects and 45 advantages of the invention which will appear hereinafter.

In the drawing Figure 1 is a view of the open end of the carrier with the slip holding means turned outwardly to permit of the insertion or removal of the message slips; Fig. 50 2 a side elevation of the carrier with a message holding means in the position shown in Fig. 1; Fig. 3 a view of the open end of the carrier, the message slip holding means being shown within the carrier; and Fig. 4 a longitudinal sectional view show-

ing the message slip holding device within the carrier.

Referring to the various parts by numerals, 1 designates the carrier body which consists of a tube of hard fiber, or other suitable material, open at one end and provided at its other end with a buffer head 2. To the inner side of the carrier and extending longitudinally thereof is rigidly secured a tube or channel 3. This tube forms a holder for the long stem or rod of the message holding clip. This tube or holder is formed with integral lugs 4 which are passed outwardly through the material of the carrier, as shown in Fig. 4, and are bent over and clenched on the outside of the carrier. The lug 4, near the open end of the carrier, is covered by a reinforcing ring or band 5 which is secured to the carrier. The inner end of the tube 3 is formed into a lug which is carried outwardly through the carrier near the buffer 2 and is then bent close to the side of the carrier. This outwardly bent end is inclosed by a cup 6. By this means the inner end of the tube 3 will be rigidly secured within the carrier and the outward strain on the message clip will not disturb the connection between the tube 3 and the carrier. Within the tube 3 is arranged a rigid tubular block 7 through which the stem 8 of the message clip extends. On the inner end of this stem is rigidly secured a collar 9 and between this collar and the block 7 is arranged a spring 10, said spring surrounds stem 8 of the message clip and forces the 80 collar 9 and the stem inwardly. Secured to the outer end of the stem 8 and fitting nicely in the tube 3 at the open end thereof is a sleeve 11, said sleeve reinforcing the rod and forming a guide for the stem within the 85 tube. Beyond the sleeve 11 the stem 8 is formed into the arch 12 the end of the arch being substantially in the same plane with the outer end of the sleeve 11. The 90 end of the rod is then coiled spirally to form a substantially flat closure device or message holding clip 13, said coil being of considerable diameter but small enough to freely fit within the open end of the carrier, as shown clearly in Figs. 3 and 4. The arch 105 12 forms a convenient handle to be grasped when withdrawing the message clip from the carrier against the tension of the spring 10.

When it is desired to place message slips in the carrier the arch 12 is grasped and the 110

message clip drawn outwardly until the flat coil 13 is beyond the open end of the carrier. The clip may then be rotated to swing the coil 13 outwardly over the end of the carrier, as shown clearly in Figs. 1 and 2. When the clip is released the spring 10 draws the flat coil closely against the edge of the carrier, the outermost turn of said coil resting on the edge of the carrier, as shown in Figs. 1 and 2. The spring will retain the holding clip in this position until it is grasped and turned into alinement with the carrier. The tube 3 and the stem 8 are so proportioned and placed in the carrier that the holding clip will be drawn into the carrier sufficiently to completely protect the arch 12. This will prevent injury to said arch and to the message clip by contacting carriers.

What I claim is:

- 20 1. A carrier comprising a tubular body, a tube therein extending longitudinally thereof, a rotatable longitudinally movable stem extending into said tube and provided with a collar on its inner end, the outer end of said stem being formed into an arch and a flat coil, said coil being adapted to fit within the open end of the carrier body and to serve as a message holding means, the said arch extending across said flat coil on the outer side thereof and serving as a handle, and a spring within the tube and bearing on the collar to force the stem inwardly.
- 30 2. A carrier comprising a tubular body, a message holding clip therefor comprising a longitudinally movable rotatable stem, means for supporting said stem within the carrier, a spring forcing said stem inwardly, a message holding clip on the outer end of said stem and formed integral therewith and consisting of an arch part and a flat coil, the arch extending across the coil on the outer side thereof and serving as a handle.

Copies of this patent may be obtained for five cents each, by addressing the "Commissioner of Patents, Washington, D. C."

3. A carrier comprising a tubular body, a message holding clip therefor, comprising a longitudinally movable rotatable stem, a tube secured within the carrier and supporting said stem, said tube terminating a considerable distance within the carrier, a spring within said tube forcing the stem inwardly, an arch formed by the outer end of said stem and a flat coil formed integral with the outer end of the arch, the arch extending across the coil on the outer side thereof, the arch and the coil lying wholly within the carrier when the clip is in its holding position.

4. A carrier comprising a tubular body part, a head permanently closing one end of said body part the other end being open, a longitudinally extending rotatable rod, means for mounting said rod on the inner surface of said body part, a spring surrounding said rod and normally forcing it inwardly, a holding clip on the outer end of said rod within the tubular body part whereby said clip will be inclosed and protected by the body part, said clip extending over a substantial portion of the interior of the carrier and transversely thereof to serve as a message holding clip, the rod being movable outwardly against the spring tension whereby the clip may be drawn outwardly beyond the end of the carrier and turned laterally away from the open end thereof to open the carrier, said clip in its turned position being drawn inwardly by the spring and caused to bear on the edge of the body part of the carrier.

In testimony whereof I hereunto affix my signature in the presence of two witnesses.

JOHN T. NEEDHAM.
